UNITED STATES PATENT OFFICE.

J. MORRIS CHILDS, OF UTICA, NEW YORK.

HARROW.

SPECIFICATION forming part of Letters Patent No. 378,081, dated February 21, 1888.

Application filed October 22, 1887. Serial No. 253,103. (No model.)

To all whom it may concern:

Be it known that I, J. MORRIS CHILDS, of Utica, in the county of Oneida and State of New York, have invented certain new and useful Improvements in Harrows; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in spring curved-tooth harrows; and it consists in the mechanism hereinafter pointed out and claimed.

In the accompanying drawings, Figure 1 represents a cross-section of the frame, clip, and curved spring-tooth. Fig. 2 represents a similar view after the tooth has been longitudinally adjusted so as to regulate the depth of the cut. Fig. 3 is a sectional view of Fig. 1 with a clip of modified construction. Fig. 4 is a top view of a portion of the frame and the top view of a clip of modified construction. Fig. 5 is a section of the frame and clip and a section of the tooth. Fig. 6 is a modified construction of clip.

In constructing harrows with my improvement I provide frames 1, (shown in cross-section,) on which frame I mount a curved spring-tooth. The curved base of the tooth is mounted on the seat 5, and is adjustable on the seat for regulating the depth of cut, and may be considered as longitudinally adjustable by means of fastening-clip 6, which spans the tooth and engages the curve horizontally only off from its bearing on the seat, so that when the tightening-nuts are applied to the clip and the clip 40 firmly engages the tooth its curve springs under the clip, and is thereby gradually straightened and held on the seat under spring tension, thereby preventing the clip and tooth from working loose by shrinkage or wear. Bolts and nuts 7 and 8, or their equivalents, 45 may be used. By loosening the nuts the tooth

may be longitudinally adjusted upon its base by moving the same under the clip, and the nuts are then tightened and the tooth held to its seat under the spring tension, as before 50 mentioned.

It may here be observed that the biting-edges of the clip, as shown in Figs. 1, 2, and 6, are desirable, as they span the inner curve of the tooth only, and thus allow a greater 55 pressure to be applied to the clip and tooth by the bolts and nuts. I do not, however, intend to limit myself to this peculiar construction, as a clip having a convex surface of less convexity than the curve of the tooth, as shown 60 in Fig. 3, may be used, as it will be observed in this case the horizontal edges only of the clip would first engage the curve of the tooth off its seat and thus hold the tooth under spring tension, as before mentioned. The tooth 65 may be seated on a flat seat on the under side of the frame, as shown in Fig. 5, in which case the clip will engage the tooth on its lower horizontal surface only.

Other modifications of my clip will readily 70 suggest themselves without departing from the spirit of my invention.

What I claim as new, and desire to secure by Letters Patent, is—

1. A harrow-frame having a flat seat, in 75 combination with a spring curved adjustable tooth and a fastening-clip adapted to engage the tooth off from its bearing on the seat on the horizontal surface of the tooth only, whereby the tooth may be longitudinally adjusted and 80 held when adjusted under spring tension.

2. A harrow-frame having a flat seat, in combination with a spring curved adjustable tooth and a fastening-clip, the ends of which engage the inner horizontal surface of said 85 tooth only.

In witness whereof I have affixed my signature in presence of two witnesses.

J. MORRIS CHILDS.
